In Sweden May 31, 1945

2 Claims. (Cl. 271—26)

1

The present invention relates to paper sheet separating and feeding machines wherein the sheets are separated one by one from a pack and each so separated sheet delivered to a printing press or other machine. Such sheet separating and feeding machines are usually provided with a single set of sheet grippers, preferably of the suction type, which are operatively connected together in unison through a system of links and cams to a driven shaft all of which limit the speed of delivery to the printing press and a primary object of the present invention is to generally improve sheet separating and feeding machines of this character whereby the sheets may be delivered in a more rapid manner.

Another equally important object of the invention is to arrange sheet grippers in sets upon a conventional separating and feeding machine and alternate the movement of each set of sheet grippers whereupon as one set of grippers move a sheet forward upon a pack towards the printing press another set of grippers will simultaneously seize or grip the next succeeding sheet of paper upon the pack and in this manner accelerate the delivery of the sheets of paper to the printing press without increasing the speed of the machine or exerting any undue strains upon the system of links and cams thereof.

Other objects of the invention are in part obvious and in part pointed out hereinafter as the description continues.

In the accompanying drawings:

Fig. 1 is a fragmental vertical sectional view of the machine embodying the invention as arranged above a pile or pack of paper sheets and,

Fig. 2 is a detail top plan view of the same.

In these drawings 1 designates a pile or pack of paper sheets to be delivered to the feed rollers B of a conveyor and which latter in turn delivers the sheets to a printing press or other machines. Extending parallel with the rear edge of the pack 1 and rotatably mounted in a suitable frame (not shown) is a driven shaft 2 and which latter rotates in that direction of the arrow as shown in Figure 1.

The shaft 1 has keyed thereto four cams indicated by the reference characters 3a, 3b, 3c and 3d. Whereas, these cams are each arranged upon the shaft in spaced relation the cams 3a and 3d are set at 180° in relation to the cams 3b and 3c. Also keyed to this shaft 2 are cams 5a, 5b, 5c, and 5d and the cams 5a and 5d are set at 180° in relation to the cams 5b and 5c. The cams 3a, 3d and 5a and 5d have a striking action at the same period of time, whereas the cams 3b,

5c, 5b and 5c also strike at the same time, but only after the shaft 2 rotates 180° after the cams 3a, 3d, 5a and 5d have struck or upon each complete rotation of the shaft 2 each set of cams is presented for striking action.

Pivotedly supported upon the fixed shaft 1 are four bell crank levers each having a downwardly extending long arm indicated by the reference characters 8a, 8b, 8c and 8d. Pivotedly connected to the lower end of each long arm of the bell crank levers is a bar and the latter are indicated by the reference characters 10a, 10b, 10c and 10d. Carried by the outer extremity of each bar is a suction cup or foot indicated by the reference characters 9a, 9b, 9c and 9d. Journalled upon the long arm of each bell crank lever is a roller 11a, 11b, 11c and 11d. A coil spring is connected to the short arm of each bell crank lever and is indicated by the reference characters 12a, 12b, 12c and 12d which normally retain said rollers in contact with the cams 3a, 3b, 3c and 3d whereby upon the rotation of the shaft 2 an oscillating movement will be transmitted to said bell crank levers and the suction cups connected thereto. Connected to each bar is one end of a link and these links are indicated by the reference characters 13a, 13b, 13c and 13d. The opposite end of each link is pivotally connected to a crank arm rotatably mounted upon the shaft 15 and is herein indicated by the reference characters 14a, 14b, 14c and 14d. Journalled upon each crank arm is a roller indicated by the reference characters 16a, 16b, 16c and 16d and which rollers are in contact with and ride upon the cams 5a, 5b, 5c and 5d. From this arrangement it is apparent that with each rotation of the shaft 2 an elevating movement will be transmitted to the bars and the suction cups carried thereby.

As the shaft 2 is rotated the cams 5a and 5d will permit the suction cups 9a and 9d to grasp a single sheet of paper upon the top of the pile 1 and then the cams 3a and 3d will strike the rollers 11a and 11d for advancing the so gripped sheet of paper until it assumes the position as indicated by the letter A in Figure 1 of the drawings. As the sheet of paper A is so advanced the cams 5b and 5c will then permit the suction cups 9b and 9c to engage the exposed end of the next sheet of paper upon the pile 1 and as the cups 9b and 9c grasp this latter sheet of paper the vacuum within the cups 9a and 9d will be broken to release the sheet A. As the sheet A has been advanced between the rollers B the latter will continue to draw that sheet across the pile and deliver the same to the printing press. As the cams

3b and 3c strike the rollers 11b and 11c the suction cups 9b and 9c will be advanced across the pile and at the same time the cams 5b and 5c will raise these suction cups and the sheet of paper carried thereby until the latter assumes the position of that sheet indicated by the letter A. As the second set of suction cups is being so actuated the first mentioned suction cups 9a and 9d will be moved rearwardly of the pile 1 under the tension of the coil springs 12a and 12d and at the same time the cams 5a and 5d will again permit the set of suction cups 9a and 9d to engage the exposed end of the next succeeding sheet of paper upon the pile 1. It will be noted that each set of suction cups grips a single sheet of paper at spaced position adjacent the rear end thereof and by alternating each set of suction cups sheets of paper may one by one be grasped from a pile and delivered to the conveyor rollers B in a more rapid manner than if only one set of suction cups were employed and yet the rotation of driven shaft 2 does not have to be increased nor will there be any undue strain on the link system between the driven shaft 2 and the several sets of suction cups. Whereas, I have shown and described only two sets of suction cups the number of sets may be increased as requirements or demands may dictate.

I claim:

1. An apparatus for separating sheets from a stack of horizontally disposed sheets and moving the separated sheets across said stack in quick succession comprising a plurality of sets of gripping members positioned above said stack of sheets, a rotary drive shaft, a group of sets of cams fixedly mounted on said shaft with one set of cams positioned at an angle of 180° relative to another set, means operable by said sets of cams for giving a horizontal oscillatory motion to each set of gripping members in succession, a second group of sets of cams fixedly mounted on said shaft with one set of cams positioned at an angle of 180° relative to another set, means operable by said second group of cam sets for giving a vertical oscillatory motion to each set of gripping members as they are moving across said stack

and means for seizing the sheets as they are advanced across said stack.

5 2. An apparatus for separating sheets from a stack of horizontally disposed sheets and moving the separated sheets across said stack in quick succession, comprising a rotary drive shaft, a pair of cam sets fixedly mounted on said shaft with a 180° angle between each set, a plurality of vertically extending bell crank levers pivotally mounted with each lever contacting one of said cams for being pivoted thereby, resilient means retaining each lever in contact with its respective cam, a plurality of horizontal arms each pivotally connected to one of said levers, a plurality of suction cups each carried by one of said arms, a second pair of cam sets fixedly mounted on said shaft with an 180° angle between each set and with each set having the same striking position as one set of said first mentioned group of cams, a second plurality of horizontal arms each bearing on one of said second group of cams, a plurality of links each pivotally connecting one of said first horizontal arms with one of said second horizontal arms.
